UNITED STATES PATENT OFFICE.

SHYE FINKELSTEIN, OF NEW YORK, N. Y.

DESIGN FOR THE ORNAMENTATION OF A NECKSCARF.

SPECIFICATION forming part of Design No. 20,642, dated March 31, 1891.

Application filed December 20, 1890. Serial No. 375,363. Term of patent 7 years.

To all whom it may concern:

Be it known that I, SHYE FINKELSTEIN, of the city, county, and State of New York, have invented and produced a new and original 5 Design for the Ornamentation of Made-Up Scarfs and Neckties, of which the following is a specification, reference being had to the accompanying drawings, and to the letters of reference marked thereon, making a part 10 thereof.

My invention relates to a new and original design for the ornamentation of made-up neck-scarfs and ties. The object thereof is to relieve the baldness and bareness of the central knot portion in a made-up scarf. 15

In the accompanying drawings, Figure 1 is an elevation of a scarf ornamented with my design, Fig. 2 being a cross-section in line *x* *x* and Fig. 3 a longitudinal section in line *y* *y* 20 of Fig. 1.

My design consists in the ornamentation, as shown in the drawings, of the face of the knot portion B of the scarf, with a bas-relief triangular in form, having its base *c* at the 25 upper end of the scarf substantially parallel with its top line. This triangular figure is

subdivided into three spaces by a line which, starting from a central point on one side of the triangle, extends substantially parallel with the opposite side thereof to the base-line 30 *c*, and by a second line which, starting from a central point on the last-mentioned division-line, extends thence substantially at a right angle therewith to the middle of the proximate outer line of the triangle. The lower 35 subdivision of the triangle is thus made to assume the form of a diamond-shaped quadrilateral, and its lower corner, constituting the apex *d* of the triangular bas-relief, is fashioned to represent the head of a living 40 creature having a nose or bill which defines the point of the triangle.

I claim as new—

The design herein shown and described for the ornamentation of a scarf. 45

In testimony whereof I have signed my name to this specification in the presence of two subscribing witnesses.

SHYE FINKELSTEIN.
